Specification of Letters Patent. Patented July 13, 1915.

Application filed August 22, 1912. Serial No. 716,398.

To all whom it may concern:

Be it known that I, EDWIN S. WOODS, a citizen of the United States, and a resident of Chicago, in the county of Cook and State of Illinois, have invented certain new and useful Improvements in Antifriction-Bearings; and I do hereby declare that the following is a full, clear, and exact description thereof, reference being had to the accompanying drawings, and to the letters of reference marked thereon, which form a part of this specification.

This invention relates to improvements in anti-friction bearings and is shown herein as applied to anti-friction center bearings designed to be interposed to transmit load between two parts which are arranged in substantially parallel relations with each other and which are capable of limited relative oscillatory movement about an axis extending substantially at right angles to them.

My improved antifriction bearing is particularly adapted for use as a center bearing between the truck and body bolster of a railway car and is herein illustrated and described as applied to that use, though it will be understood that it is in no way limited thereto.

The invention as illustrated herein is embodied in a species of that genus of antifriction center bearing disclosed and broadly claimed in Letters Patent No. 995835, granted to me on June 20, 1911, and consists of certain novel modifications and improvements applicable not only to the center bearing therein disclosed, but also to other forms of bearings.

A center bearing provided with the improvements of the present invention is like the construction disclosed in the patent referred to in that it comprises a plurality of antifriction elements interposed between relatively oscillatory bearing members, all of said antifriction elements being adapted to oscillate on axes radial to the axis of oscillation of said bearing members and having contact at their bottom and top surfaces with said bearing members and the cross-section of each anti-friction element taken at right angles to its axis of

oscillation approximating the section of load transmission. The section of load transmission referred to is that part of the cross section of the anti-friction element included by or within the upper and lower arcs on which said section rolls during an oscillation of the greatest required amplitude and defined laterally by right lines connecting the ends of said arcs, and which forms, in effect, the cross sectional area of load transmission.

In the drawings—Figure 1 is a view representing a vertical central section through a center bearing embodying my improvements, the antifriction elements in this case being parts of cones. Fig. 2 is a view representing a horizontal section through Fig. 1 in a plane indicated by the line 2—2 thereof. Figs. 3 and 4 are perspective views of one of the antifriction elements looked at from opposite sides. Figs. 5 and 6 are views representing cross-sections through the anti-friction elements in the cylindric surfaces extending through the lines 5—5 and 6—6, respectively, of Fig. 2. Fig. 7 is a view similar to Fig. 2 showing a construction containing a modified form of the anti-friction element. Figs. 8 and 9 are perspective views of adjacent antifriction elements of the modified form. Figs. 10 and 11 are views representing vertical sections through the antifriction elements in the vertical cylindric surfaces indicated by the lines 10—10 and 11—11, respectively, of Fig. 7.

In illustrating the invention I have shown it as applied to that type of antifriction element which is capable of use in a center bearing and in which the bearing surfaces of said elements are conical, this type being the most convenient for purposes of illustration, but it will be understood that the term "antifriction element" as used herein includes other types of antifriction elements capable of use not only in center bearings, but in other bearings, as, for example, those having spherical or cylindric bearing surfaces, and that the invention is not limited to the type illustrated.

Referring now to the drawings, and particularly to that embodiment of my invention illustrated in Figs. 1 to 6, inclusive,—

11 represents the upper member and 12 the lower member of a car center bearing. The upper member 11 is made integral with a centrally disposed sleeve 13 adapted to receive the king pin. The lower bearing member is preferably made in two parts 12^a, 12^b, the one placed upon the other, and the two parts having spherical engaging faces to provide a universal bearing between them.

14 indicates a plurality of annularly arranged antifriction elements which are engaged between the upper and lower bearing members 11 and 12 and are adapted for oscillatory movement on horizontal axes radial to the vertical axis about which the said bearing members themselves oscillate.

Each antifriction element, as shown in Figs. 1 to 11, has top and bottom conic bearing surfaces, tapering from its outer end inwardly. The lateral faces of the antifriction elements have one or more longitudinally spaced parts which project beyond the section of load transmission of said elements, and one or more longitudinally spaced cut-away or recessed parts, arranged in alternation with said projecting parts, the projecting parts and the recessed or cut-away parts of the contiguous faces of adjacent elements being relatively arranged in such manner that the projecting part of each element projects or mortises into a recessed or cut-away part in the contiguous face of the adjacent element.

35 In the form of the invention shown in Figs. 1 to 6, inclusive, all of the antifriction elements are alike. Each element has on one lateral face full conical parts 15 and 16 (see Fig. 4), located respectively adjacent its outer and inner ends and an intermediate cut-away or recessed part 17, while on its opposite lateral face it has cut-away or recessed parts 18, 19 located respectively at its outer and inner ends and an intermediate full conical part 20. The recessed or cut-away parts and the projecting parts are so arranged and proportioned and the antifriction elements are assembled in the bearing in circular order in such manner that the 45 projecting part 20 of each element will project or mortise into the recessed or cut-away part 17 in the contiguous face of the adjacent element, while the projecting parts 15, 16 of the latter mentioned element will 50 mortise into the cut-away or recessed parts 18 and 19 of the first-named element.

As shown in Figs. 7 to 11, the adjacent antifriction elements 14^a, 14^b are different in that the one 14^a has on each lateral face full 60 conical parts 21, 22 located adjacent its inner and outer ends respectively and an intermediate recessed or cut-away part 23 (see Fig. 8) while the adjacent element has on each face cut-away or recessed parts 24 and

25 adjacent its outer end and inner end respectively and an intermediate full conical part 26. When assembled the full conical parts of each antifriction element mortise into the recessed or cut-away parts of the adjacent element just as in the first case.

It will be noticed that with the mortise and tenon arrangement by which the full conical parts of the antifriction elements engage with the recessed or cut away parts of the adjacent elements, as illustrated in the drawings, the end surfaces of the lateral projections of the elements engage the contiguous end surfaces of the recessed or cut away portions of the adjacent elements in such manner that each element resists the end thrust of the adjacent elements.

The lateral faces of the antifriction elements at the recessed or cut-away parts have intermediate conical surfaces, concentric with the cones of which the elements as 85 wholes form parts, said conical surfaces being adapted for bearing engagement against the associated full cone projections of the adjacent elements which dove-tail into the recesses, and above and below the same, reversed conical surfaces 28, 28 of substantially the same diameter as said full conical projections. Said surfaces 27 and 28 are so proportioned in vertical extent relatively to the height of the antifriction elements, that 95 when said elements have been oscillated in one direction through one-half of the maximum amplitude of oscillation that they are designed to have, the projecting conical parts of the elements will come to bear in 100 the reversed curved conical surfaces 28 of the adjacent elements and thus lock said elements against further movement in that direction.

The upper bearing member 11 has a short 105 depending annular flange 29 adapted to take the end thrust of the antifriction elements. The inner bearing surface 30 of said flange is spherical, the center of the sphere being substantially coincident with the common 110 point in the vertical axis of oscillation of the bearing members in which the axes of the conical surfaces of the antifriction elements meet. The end surfaces 31 of the antifriction elements likewise are spherical, 115 the end surfaces of all the assembled antifriction elements when in assembled relation coinciding with the surface of a sphere concentric with the spherical surface 30 of the end thrust flange 29. This feature of the 120 construction is essential since if the ends of the antifriction elements be made flat, the end thrust flange will force the antifriction elements endwise toward the center of the bearing as they oscillate to one side or the 125 other causing the upper and lower bearing members to be thrust apart in a vertical direction. The surfaces of the shoulders 32

defining the ends of the latter projections of the antifriction elements are also made spherical for the same reason.

The antifriction elements are provided at each end with projecting lugs or trunnions 33, 33^a and a radially extending horizontally annular flange 34 is provided on the sleeve 13 and a corresponding similar flange 35 is provided at the outer periphery of the upper bearing member to engage said lugs or trunnions and prevent the antifriction elements from falling from their assembled relation in the upper bearing member when said antifriction elements are not supported by the lower bearing member.

As shown herein, the upper bearing member is made in two parts, a part including the bearing plate proper 11^a and a band or ring 36 which fits snugly about the outer periphery of said bearing plate and has an annular shoulder 36^a against which a corresponding annular shoulder 11^b on said bearing plate bears. A tight fit is preferably made between the two parts so that they will be held together by friction. The outer supporting flange 35 is provided on the ring 36 and by reason of this construction both retaining flanges 34, 35, may be made continuous and unbroken, the antifriction elements being assembled before the ring 36 is forced upon the plate 11.

The upper bearing member is recessed or depressed to form a chamber 37 for containing hard oil or grease and said plate has perforations 38 arranged as shown in radially extending lines above each antifriction element and adapted to permit the passage of the oil or grease to the bearing surfaces of said elements. The elements themselves are each provided with one or more apertures 39 in that part of their end surfaces which engage with the end thrust flange 29, and with one or more apertures 40 in their lateral faces as, for example, in the conical lateral projections 15, 16 and 20 (see Figs. 3 and 4,) and 21, 22 and 26 (see Figs. 8 and 9,) which apertures are designed to contain hard oil or grease for lubricating the bearing between the end thrust flange 29 and the ends of the antifriction elements and the bearings between the lateral faces of the adjacent elements.

The lugs 33^a at the inner-ends of the antifriction elements are provided with flat lateral faces 33^b, 33^b, which are so constructed that the lateral faces of the said lugs of the antifriction elements when assembled are closely adjacent to each other. This construction prevents the antifriction elements from turning over on their sides and acts to hold them in proper vertical position.

While in describing my invention I have referred to certain details of construction and arrangement as embodied in the preferred form of my invention, it is to be

understood that the invention is not limited thereby except as pointed out in the appended claims.

I claim as my invention—

1. An antifriction bearing, comprising bearing members and an interposed series of antifriction elements, each antifriction element having on its lateral face one or more longitudinally spaced projecting parts and one or more recessed parts longitudinally adjacent to said projecting parts, such projecting parts of each antifriction element extending into the recessed parts of the adjacent antifriction elements.

2. An antifriction bearing, comprising bearing members and an interposed series of antifriction elements, each antifriction element having on each lateral face one or more longitudinally spaced projecting parts and one or more recessed parts longitudinally adjacent to said projecting parts, such projecting parts of each antifriction element extending into the recessed parts of the adjacent antifriction elements, and the ends of the projecting parts of the several antifriction elements having thrust bearing against the ends of the projecting parts of the adjacent elements.

3. An antifriction bearing, comprising relatively oscillatory bearing members and an interposed series of annularly arranged radially disposed, antifriction elements, all of which are adapted to oscillate on axes located intermediate said bearing members, the average mean cross sectional area of the several anti-friction elements taken at right angles to their axes of oscillation being substantially equal to their sections of load transmission, and each antifriction element having on each lateral face one or more longitudinally spaced projecting parts and one or more recessed parts longitudinally adjacent to said projecting parts, such projecting parts of each antifriction element extending into the recessed parts of the adjacent anti-friction elements.

4. An antifriction bearing, comprising relatively oscillatory bearing members and an interposed series of annularly arranged, radially disposed, antifriction elements, all of which are adapted to oscillate on axes located intermediate said bearing members, the average mean cross sectional area of the several anti-friction elements taken at right angles to their axes of oscillation being substantially equal to their sections of load transmission, and each antifriction element having on each lateral face one or more longitudinally spaced parts projecting beyond its section of load transmission and one or more recessed parts longitudinally adjacent to said projecting parts, such projecting parts of each antifriction element extending into the recessed parts of the adjacent anti-friction elements.

5. An antifriction bearing, comprising relatively oscillatory bearing members and an interposed series of annularly arranged, radially disposed, antifriction elements, all of which are adapted to oscillate on axes located intermediate said bearing members, the average mean cross sectional area of the several anti-friction elements taken at right angles to their axes of oscillation being substantially equal to their sections of load transmission, and each antifriction element having on each lateral face one or more longitudinally spaced parts projecting beyond its section of load transmission and one or more recessed parts longitudinally adjacent to said projecting parts, such projecting parts of each antifriction element extending into the recessed parts of the adjacent antifriction elements and said elements being each provided with radial lugs at their inner ends having flat sides, the flat sides of said lugs of adjacent elements being closely adjacent.
6. An antifriction bearing, comprising relatively oscillatory bearing members and an interposed series of annularly arranged, radially disposed, antifriction elements, all of which are adapted to oscillate on axes located intermediate said bearing members, the average mean cross sectional area of the several antifriction elements taken at right angles to their axes of oscillation being substantially equal to their sections of load transmission, and each antifriction element having on each lateral face one or more longitudinally spaced, inwardly tapering, conical parts projecting beyond its section of load transmission and one or more recessed parts longitudinally adjacent to said projecting parts, the projecting parts of each antifriction element extending into the recessed parts of the adjacent antifriction elements.
7. An antifriction bearing, comprising relatively oscillatory bearing members and an interposed series of contiguous, radially disposed, antifriction elements, all of which are adapted to oscillate on axes located intermediate said bearing members, the average mean cross sectional area of the several antifriction elements taken at right angles to their axes of oscillation being substantially equal to their sections of load transmission, and each antifriction element having on each lateral face one or more longitudinally spaced, inwardly tapering conical parts projecting beyond its section of load transmission and one or more recessed parts longitudinally adjacent to said projecting parts, said projecting parts of each antifriction element mortising into the recessed parts of the adjacent elements, and the lateral faces of said antifriction elements at the recessed parts having an intermediate, longitudinally extending, conical part of smaller radius than said projecting parts, and an upper and lower reversed curved conical part of substantially the radius of the bearing surfaces of said antifriction elements.
8. An antifriction bearing, comprising relatively oscillatory bearing members and an interposed series of contiguous, radially disposed, antifriction elements, all of which are adapted to oscillate on axes located intermediate said bearing members, the average mean cross sectional area of the several antifriction elements taken at right angles to their axes of oscillation being substantially equal to their sections of load transmission, and each antifriction element having on each lateral face one or more longitudinally spaced, inwardly tapering, conical parts projecting beyond its section of load transmission and one or more recessed parts longitudinally adjacent to said projecting parts, said projecting parts of each antifriction element mortising into the recessed parts of the adjacent elements, and the lateral faces of said antifriction elements at the recessed parts having an intermediate, longitudinally extending, conical part of smaller radius than said projecting parts, and an upper and lower reversed curved conical part of substantially the radius of the bearing surfaces of said antifriction elements, the lateral faces of said antifriction elements being provided with recesses to contain a lubricant for the bearing between the contiguous parts of said faces.
9. An antifriction bearing, comprising relatively oscillatory bearing members and an interposed series of annularly arranged, radially disposed, antifriction elements, all of which are adapted to oscillate on axes located intermediate said bearing members, the average mean cross sectional area of the several antifriction elements taken at right angles to their axes of oscillation being substantially equal to their sections of load transmission, and each element having on each lateral face one or more longitudinally spaced parts projecting beyond its section of load transmission and one or more recessed parts longitudinally adjacent to said projecting parts, the projecting parts of each antifriction element mortising into the recessed parts of the adjacent elements and being adapted for bearing engagement in said recessed parts.
10. An antifriction bearing, comprising relatively oscillatory bearing members and an interposed series of annularly arranged, radially disposed, antifriction elements, all of which are adapted to oscillate on axes located intermediate said bearing members, the average mean cross sectional area of the several antifriction elements taken at right angles to their axes of oscillation being sub-

stantially equal to their sections of load transmission, and each antifriction element having on each lateral face one or more longitudinally spaced parts projecting beyond its section of load transmission and one or more recessed parts longitudinally adjacent to said projecting parts, said projecting parts of each antifriction element mortising into the recessed parts of the adjacent elements, and said projecting parts terminating

in transversely extending shoulders having concentric, spherical bearing surfaces.

In testimony, that I, claim the foregoing as my invention I affix my signature in the presence of two witnesses, this 16th day of 15 August A. D. 1912.

EDWIN S. WOODS.
